UNITED STATES PATENT OFFICE.

JOHN GEORGE SCHERF AND ZACK FORT FAEMER, OF ANDALUSIA, ALABAMA.

GARMENT.

Application filed June 29, 1925. Serial No. 40,203.

The present invention relates to a garment for both adults and children and has particularly to do with a slit opening therein and the manner in which such opening is produced.

In application, the invention may include waist suits, rompers, overalls, coveralls, unionalls, underwear and pajamas for children, and for men's and youths' wear, union suits, overalls, pajamas and similar garments. The material of which these garments may be made is immaterial for the structure lends itself to adaptation to use with any suitable material.

15 Among the objects of the invention are the following:—

The provision of an improved garment having a slit opening;

20 A new and novel way for providing a slit opening in a garment of the types described;

An unique way of reinforcing the material of a garment adjacent an opening therein;

Improved means for providing a slit opening in a garment and for giving great strength 25 to the material adjacent such opening, conjointly providing a neat finish; and

The employment of a facing or strip upon a garment having a side or other opening whereby comfort for the wearer is attained 30 while strengthening the material adjacent such opening.

These and such other objects as may hereinafter appear are obtained by the novel combination, construction and arrangement of 35 the elements constituting the invention, a single embodiment of which is disclosed in the accompanying drawing, and in which:—

Figures 1, 2, and 3 show the patterns required to produce a garment such as is illustrated in the succeeding figures; Figure 1 40 being the seat or back of leg of a garment with side seams; Figure 2 being the front with the body and leg cut in one piece; and Figure 3 the back.

45 Figure 4 shows a garment embodying the invention; and

Figures 5, 6, 7 and 8 disclose three stages in the production of a side opening in a garment like that in Figure 4.

50 Like reference characters are used to designate similar parts in the drawing and in the description which follows.

It must be distinctly understood at the out-start that the garment illustrated in Figure 4 55 is but one of the many types of garments in which the invention may be employed to ad-

vantage, and also, that the particular pattern of the garment now to be described may be variously changed without departing from the spirit of the invention.

60

An undergarment is selected for illustrative purposes only.

Several portions of material cut in accord with the patterns illustrated in Figures 1, 2 and 3 are joined one to another to produce a garment such as is shown in Figure 4, which is a back view of such a garment. The reinforcing shown in the seat is frequently supplied and is cut from a separate pattern not here shown. And as it will later be quite 70 manifest, the construction employed upon the side opening may be used with equal facility upon a front or back opening garment.

By reference to Figure 1, it will be seen that the material of the seat S adjacent the 75 side seam is slit as indicated by the numeral 5. As shown in Figure 5 the narrow strip of material 6 is turned down and to the edge formed by said slit 5, one or more strips of material 7 which may be called "facings" and 80 which may be of various widths and lengths are stitched therein. The numbers and character of facings 7 are matters for the designer of the garment to determine as is also the length of slit 5.

When the end of the slit 5 is reached during the stitching of the facings 7 to the seat S the operator picks up the turned down strip 6 and continues his stitches through the strips 7 thereinto. The stitching, which may be in several rows is extended to the end of strip 6. The order of these operations could be reversed and the facings 7 sewed first onto strip 6. A row of stitches 8 is arranged across the facings 7 at the point where said strips 7 95 cease to be fastened to the seat S of the garment and become attached to strip 6.

The strip 6 carrying the facing 7 is adapted to be secured to the front portion of the garment and to thereby add to such front at the 100 side seam 9 a narrow portion of material.

By cutting the material as indicated at 5, attaching thereto a continuous facing or facings 7, and placing the transverse stitching at the point 9 of jointure between said strip 6 105 and the garment proper, a reinforcement around the opening is obtained. Both sides of said opening are equally well reinforced by a continuous strip or its equivalent and the garment is strongest at this section. A 110 very neat finish is provided and there is great comfort to the wearer for the two sides of

the material at the opening align themselves in a way preventing bunching or undue overlapping of the material.

- When the front of the garment is joined thereto, the side seam 9 extends from the belt or waist downwardly on the forward edge of strip 6 reinforced by facings 7 until the transverse stitching 8 is reached, where the seam 9 follows the edge of the back leg section to the bottom thereof. An unique feature of this construction is that the material of the garment adjacent the jointure of strip 6 and the leg portion secures a natural separation between the several sections of the garment.
- This is not such a separation as to cause the opening to spread for on the contrary it remains closed, but it is sufficient to distinguish the parts and show the termination of the opening.
- The garment as to its other parts may be conventionally made. As to the position of a side opening made in accord with the invention, it may be further forward or more toward the back than shown. This is another detail which is determined by the cutter or

the designer of the garment. Ripping of the garment at the opening is practically impossible because of the superior manner in which it is reinforced by a continuous member.

We claim:

The method of manufacturing a garment having a drop seat with the usual and incidental openings at the side thereof which consists in cutting the portion of the garment, consisting of a front, upper back and lower back, slitting the lower back longitudinally at the top and near the sides thereof, sewing a single strip of material along the cut edges of said slit and sewing the upper and lower rear portions to the front portion with the upper and lower rear portions partially overlapping, the small portion of material resulting from the slit, together with one part of said sewed in strip being included in the seam with the front portion of the garment and the lower edge of the upper rear portion.
